(57) **CLAIM**

The ornamental design for a fastening device locking piece
as shown and described.

DESCRIPTION

FIG. 1 is a bottom perspective view of a fastening device
locking piece showing my new design;

FIG. 2 is a second bottom perspective view of the fastening
device locking piece of FIG. 1;

FIG. 3 is a bottom plan view of the fastening device locking
piece of FIG. 1;

FIG. 4 is a top plan view of the fastening device locking
piece of FIG. 1; and,

FIG. 5 is a top perspective view of the fastening device
locking piece of FIG. 1.
